L. FARKAS

BUST SUPPORTER

Filed March 26, 1925

Louis FARKAS,

Inventor

By his Attorney Julian J. Wittig

UNITED STATES PATENT OFFICE.

LOUIS FARKAS, OF NEW YORK, N. Y.

BUST SUPPORTER.

Application filed March 26, 1925. Serial No. 18,624.

This invention relates to underwear for women and especially to the type of underwear as is known under the names brassière, bandeau, bust supporter, bust belt, etc. I 5 prefer to call my invention a bust supporter and the main object of the same is to provide an under garment of the character mentioned which will be pleasant and comfortable to wear and which will be artistic, attractive and hygienic.

Other objects of my invention are: to provide a bust supporter which will give to the bust of the wearer an attractive desirable contour and shape, which will be healthful 15 to wear, which may be applied in an inconspicuous manner directly on the body, which will be light in weight, cheap to manufacture and easy to clean, which will prevent the bust of the wearer from moving or from 20 rubbing against the body, this latter service making it especially desirable in hot weather.

Still further objects will be apparent as the description of my invention proceeds.

25 To these ends the invention comprises the novel features of improvement and details of construction, which will be hereinafter described, and finally set forth in the claims.

30 The accompanying drawing is a perspective view of a bust supporter made according to my invention.

Referring to the drawing, my bust supporter comprises the main body 10 which 35 is of a belt shape, adapted to encircle the body of the wearer at the height of the busts, and has the means 11 at its ends to secure them together at the back of the wearer. Two semispherical bust supporters 40 proper 12 are arranged in the front portion of the belt body 10 and means 13 help to keep said belt in a proper position by suspending the same from the shoulders of the user.

45 In the modification of my invention shown on the drawing, the main belt body 10 is composed of two halves 14 and 15 joined as at 16 in which place both halves may be reinforced by doubling up the marginal ends 50 of them or possibly also by arranging a suitable strip of material underneath the seam. For easier manufacture and also to give a desired shape and increased stiffness to the belt, it may have the two additional 55 cuts, and reinforced seams 17 and 18, in its two respective halves.

The bust holding semispheres 12 are preferably made of four segments 19 joined by reinforced seams 20. The reinforcing of these seams may also be done by doubling 60 the ends of the material or by strips of material being placed underneath them and sewed to the segments, or by both. The seam joining the segments 19 and the belt halves 14 and 15 may be left without any 65 special reinforcing and made of single or double sewing as at 21. In a similar manner the upper and lower edges 22 and 23 of the belt body may be finished by doubling up the material and providing it with 70 one or two rows of stitches, while the upper edge 22 may, in addition to this, have the lace 24 or some other ornament secured along its line.

The belt body shows the largest dimension in width in the front portion of the same, having suitably and artistically curved upper and lower contours at this portion. The belt then gradually diminishes in width towards its two ends 25 and 26. The end 25 in the modification shown carries elastic strips 27 gradually diminishing in length and with button holes 28 at their ends, while the belt end 26 may carry the buttons 29. In providing the gradually 75 diminishing lengths for the securing strips 27 allowance is made for the shape of the human body at this point. It is to be understood that any other suitable and well known 80 means may be employed, instead of the strips and buttons shown, to secure the ends 85 of the main belt together.

The means used for suspending my brassière from the shoulders of the wearer may in the simplest case take the form shown 90 which is a shoulder strap 13 secured to the rear portion of the main belt in a permanent manner, while buttons 31 and button holes 32 may be used in the front parts of the belt and straps, respectively, permitting 95 an adjustable and removable connection between said two elements of my brassière.

The brassière is shown as of woven textile material but it may be made of knitted materials and in one piece as against the several 100 pieces shown in the drawing. I also want it to be understood that other changes and variations may be made in the construction of the parts within the limits of the claims 105 without departing from the spirit and scope 110 of the invention.

What I claim as new, is:

1. A bust supporter comprising a belt like body having breast pockets, each having crossed reinforcing strips, said body being further reinforced between the breast pockets by an inverted cross-like thickened portion, the horizontal portion of the reinforce being wider toward the center to 15 stiffen the structure at that point, in combination with adjustable shoulder straps and back straps of graduated length to draw the supporter into smoother contact with the body.
2. A bust supporter comprising a belt like body having breast pockets, each having crossed reinforcing strips, said body being further reinforced between the breast

Signed at New York, in the county of New York and State of New York, this 17th day of September A. D. 1924.

LOUIS FARKAS.
